UNITED STATES PATENT OFFICE

OWEN AVIS PEARCE, OF LIVERPOOL, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed September 27, 1928, Serial No. 308,754, and in Great Britain October 10, 1927.

The present invention relates to telephone systems and is more particularly concerned with so-called routining apparatus, that is to say, apparatus designed to simulate for test purposes the conditions which will be encountered by certain apparatus under normal conditions of working and to give an indication of any irregularity which may occur due to faulty operation of the apparatus. The arrangement according to the present invention is particularly applicable to the testing of apparatus used in the setting up of calls from automatic to manual exchanges with call indicators at the manual operator's positions.

It has been found desirable in some cases to transmit the wanted number over the trunk line to the manual exchange in code in order to save time, and in this case it is necessary to have a register switch at the automatic exchange to receive the impulses from the calling party and to convert them into the appropriate code pulses. Conveniently, this is done as in the arrangement shown in British Patent No. 229,371 by employing a repeater at the outgoing end of the trunk line, the repeater being provided with arrangements for associating with itself a suitable register sender conveniently termed a coder.

The present invention will be described in connection with the testing of such a repeater and it will be appreciated that the test must include the transmission to the coder of a suitable test number and the checking of the code impulses sent out therefrom in response to the registration of this number.

In a telephone system in which calls from an automatic subscriber are routed to a manual call indicator exchange by way of a tandem exchange, such repeaters are inserted in the trunk line to the manual call indicator exchange and the present invention has been primarily designed for testing the various functions of such repeaters.

Such repeaters may be of the type shown and described in British Patent No. 268,058 with the exception of the addition of a further switching relay for routining facilities,

the full purpose of which will be apparent from the detailed description which follows later.

The routiner is arranged to simulate the working conditions normally imposed on these repeaters and to check the correct functioning of the repeater at each stage of the call, together with such features of the register sender as are necessary to completely follow working conditions. Further, the tests imposed include arrangements to check the condition of the outgoing junction with which the repeater is associated to provide a transmission test through the repeater transmission bridge, to test for the correct metering condition, to check the operation of the repeater on receipt of a busy signal, and to test for the guarded condition during release of the circuit. In addition, marginal limit tests are applied to certain of the repeater relays, for example, the impulses accepting relay so that the correct adjustment of such important relays may be verified, in addition to the test under average working conditions.

The routining equipment is arranged to deal successively with a large number of repeaters, in the case of the drawings attached hereto as many as 960. Access to the repeaters is obtained essentially by means of primary and secondary distributors of which there are shown in the drawings two primary distributors having access to 48 secondary distributors each of which is arranged to deal with 20 repeaters. The arrangement of this distributing apparatus is substantially identical to that described in British Patent No. 292,691 and it will be readily obvious to those versed in the art that this arrangement may be extended if desired so that access may be obtained to whatever number of repeaters may be equipped at any particular exchange.

The general scheme of operation is, briefly, that once the routiner is started, each repeater in turn is subjected to a series of tests and the operation continues automatically until all have been dealt with unless a fault is found. In this case the routining operation is stopped and suitable

lamps indicate the particular repeater on which the fault has been found and also the nature of the fault.

In order that the invention may be more fully understood a detailed description will now be given, reference being had to the accompanying drawings comprising Figs. 1 to 10, inclusive, which show by means of the usual circuit diagrams sufficient of the apparatus employed to enable the invention to be understood. It will be understood, however, that this is given by way of example only, and that various modifications may be made in the circuit details by those skilled in the art without departing from the spirit or exceeding the scope of the invention. These drawings should be arranged with Fig. 2 to the right of Fig. 1, Figs. 3, 5, 7 and 9 below Fig. 1, and each other in order, and Figs. 4, 6, 8 and 10 below Fig. 2, and each other in order with the interconnecting lines in alignment. Figs. 1 and 2 show two primary distributors PD^1 and PD^2 and a secondary distributor SD , while it will be understood that other secondary distributors not shown are connected to the banks of the primary distributors PD^1 and PD^2 ; Fig. 3 shows the control switch CS which controls the connection of each testing condition, while the remaining figures show various relays associated with the invention together with sundry keys included for purposes which will be followed from the detailed description hereafter.

A description will first be given of the operation of the distributor equipment. When it is desired to start the routine tests the start key 10 (Fig. 10) is operated, thereby causing the operation of relays S and SS over the circuits: earth, key 10 in operated position, conductor 11 to the winding of relay S (Fig. 6) to battery; and earth, key 10, conductor 12 to relay SS (Fig. 4) to battery. When relay S operates, earth pulses for instance at the rate of 10 per second are connected from conductor 19 (Fig. 4) resting springs of step-on key 13, armature 14 and back contact, conductor 15, armature 16 and front contact (Fig. 6) armature 17 and back contact, armature 18 and back contact, winding of relay P to battery. Relay P now operates in synchronism with the earth pulses. Furthermore, earth pulses at conveniently the rate of 40 per minute are connected from conductor 20 (Fig. 6) armature 21 and front contact, armature 22 and back contact, winding of relay DR (Fig. 6) to battery. Relay DR pulses over the circuit described, throughout the remainder of the test, or until the alarm relay AM is operated.

Returning now to relay P which it will be remembered is pulsing, on its first energization earth is extended from armature 23, conductor 24, armature 25 and back con-

tact, conductor 26, armature 27 and back contact, conductor 28, upper winding of relay DA (Fig. 4) to battery. Relay DA closes its light armature 29, and the lower winding is held short-circuited until relay P restores. Earth is connected to the right hand terminal of the lower winding of relay DA over back contact and armature 25, conductor 24, armature and front contact 23 and earth is connected to the left-hand terminal of the lower winding of relay DA over armature 29 and front contact, conductor 30, front contact and armature 31. On the restoration of relay P , relay DA operates all its armatures both its windings being energized in series over the following circuit: earth, armature 31 and front contact (Fig. 6), conductor 30, front contact and armature 29 (Fig. 4), lower winding of relay DA , conductor 26, armature 27 and back contact (Fig. 6) conductor 28, upper winding of relay DA to battery.

On the next energization of relay P two circuits are completed, the first as follows: earth, armature 23, conductor 24, armature 25 and front contact, (Fig. 4), armature 32 and back contact, conductor 33, winding of relay TC (Fig. 6) to battery, and parallel thereto, from conductor 33, over armature 34, upper winding of two-step relay DB to battery. Relay TC operates fully, and relay DB closes its light armature 38, its lower winding being then short-circuited until relay P restores, since earth is connected to its left-hand terminal as follows: earth, armature 31 and front contact, armature 39 and back contact, armature 38 and front contact, and to the right-hand terminal as follows: earth, armature 23, conductor 24, armature 25 and front contact, armature 32 and back contact, conductor 33, armature 34 and front contact, conductor 35, armature 36 and back contact, conductor 37, to right-hand terminal. The second circuit is from earth, armature 40 (Fig. 6) conductor 41, armatures 42, 43, 44 and 45 (Fig. 4), conductor 46 (Fig. 3), wiper 47 of primary distributor PD^1 (Fig. 1) bank contact 1, conductor 48, winding of driving magnet DM^1 of secondary distributor SD to battery. The magnet energizes and remains energized until relay P releases, at the end of the pulse, whereupon it moves the wipers of the secondary distributor forward one step so that they are now in contact with the repeater circuit in readiness for the commencement of the test. The release of relay P also removes the short circuit from the lower winding of relay DB , and relay DB operates all its armatures since both its windings are now energized in series over the following circuit: earth, armature 31 of relay S , armatures 39 and 38, lower winding of relay DB , conductor 37, armature 36, conductor 35, upper winding of relay DB to battery.

DB to battery. The operation of relay DB opens the circuit of relay DA at armature 27; opens the circuit of the pulsing relay P at armature 17; opens its own initial energizing circuit at armature 34 and prepares various other circuits for the commencement of the routine test. It will be seen that relays P and DA cannot re-operate to step the secondary distributor until relay DB is released, and relay DB is now controlled by relays TO and KA.

The operation of start relays S and SS when the start key was thrown effects a number of circuit changes which will be described later.

It will be sufficient here to point out that the homing circuits of the various distributor switches are opened at armatures 49, 50, 51, 52, 53, 54 and 55 of relay SS and that earth is connected over armature 54 and front contact, armature 156, conductor 57, wiper 58 of primary distributor PD¹, and its first bank contact to the first group indicating lamp 59 to battery, to show the group in which the repeater under test is located. Moreover, earth is extended from wiper 60 of the secondary distributor SD to the first individual indicating lamp 61, so that the lighting of these two lamps will always show exactly which repeater is under test. The leads to the individual indicating lamps it will be understood are multiplied in the corresponding banks of all secondary distributors.

The routining operation will now commence and will proceed in a manner to be described shortly, and when it is completed the wipers of the control switch CS (Fig. 3) will be on contact 23, and relay TO will operate from earth, springs controlled by armature 62 of relay KA (Fig. 8) conductor 63, armature 64 and front contact, conductor 65, resting springs of reset key 66, conductor 67 (Fig. 10, 8, 7, 5 and 3), wiper 68 of control switch CS resting on bank contact 23, conductor 69 (Figs. 3, 5 and 6) winding of relay TO to battery. The operation of relay TO opens contacts 39 and thus breaks the circuit of relay DB which releases thereby allowing contacts 17 to close.

The earth impulses from conductor 19 (Fig. 4) are now extended to relay P as before, and it operates thus energizing the upper winding of the two-step relay DA which operates completely when relay P restores at the end of the pulse. The further operation of relay P, DA, DB and TC and the stepping of the secondary distributor so that the testing conductors are connected to the next repeater is similar to that described previously.

The full operation of relay DB completes a circuit as follows: earth, springs controlled by armature 62 of relay KA, (Fig. 8), conductor 63, armature 64 and front

contact, conductor 65 (Figs. 8, 10 and 9) winding of relay RS to battery. Relay RS operates over the circuit described and connects earth from armature 70, conductor 71, first bank contact and wiper 72 of control switch CS (Fig. 3) interrupter springs 73, winding of driving magnet DM⁶ to battery, thus causing the control switch to step its wipers to the first position in readiness for the next test cycle.

Relay DB will again remain locked up after the secondary distributor is stepped till the control switch again reaches contact 23 and relay TO is re-operated.

It will be seen that owing to the advance of the secondary distributor, the second individual indicating lamp will glow whilst the group lamp is not altered. The test now proceeds on this repeater and when it is completed the secondary distributor will take another step in a similar manner. When all the twenty repeaters connected to the banks of the first secondary distributor have been thus dealt with, a circuit is completed for relay TO to operate as before, and in this case the operation of TO in addition to opening the circuit to relay DB, closes the circuit of relay TS (Fig. 4) in parallel with the 20th individual indicating lamp. This circuit may be traced as follows: earth, wiper 60 of secondary distributor resting on contact 20, conductor 74, front contact and armature 75, conductor 76 (Figs. 6, 5, 3 and 4) armature 77 and back contact, winding of relay TS to battery. Relay TS upon operating locks up in the following circuit: earth, armature 31 (Fig. 6) conductor 30, armature 79 and front contact, armature 78 and back contact, winding of relay TS to battery.

The operation of relay TO opened the circuit of relay DB at armature 39, allowing relay DB to release and on the commencement of the next pulse from relay P, a circuit is completed from earth, armature 40 and front contact (Fig. 6) conductor 41, armature 42 and front contact, armature 43 and front contact, back contact and armature 80, armature 81 and back contact, conductor 82, winding of driving magnet DM⁴ of primary distributor PD¹ to battery, so that the magnet is energized.

When relay P releases after the pulse, magnet DM⁴ also releases and advances the first six wipers of the primary distributor forward one step. Earth is now extended from armature 54 and front contact of relay SS, armature 156 and back contact, conductor 57, wiper 58 of primary distributor PD¹, bank contact 2, to the second group indicating lamp, and also over conductor 83, first bank contact and wiper 84 of the auxiliary part of the primary distributor PD¹, interrupter springs 85, winding of magnet DM⁵ to battery. The magnet energizes,

breaks its circuit at the interrupter springs 85 and releases, thus moving the second six wipers of the primary distributor forward one step. The resultant effect is therefore as if all twelve wipers of the primary distributor were controlled by one magnet. When relays P, DA and TS are energized a circuit is also completed for the two-step relay DC as follows: earth, armature 23 of relay P, conductor 24, armature 25 and front contact, armature 32 and front contact, lower winding of relay DC to battery. Relay DC closes its light armature 86 at this period; its upper winding being then short-circuited till relay P releases at the end of the pulse. When this occurs, relay DC operates its armature 78 since both its windings are energized in series over the following circuit: earth, armature 87 and front contact, armature 86 and front contact, both windings of relay DC in series to battery. The locking circuit of relay TS is now broken at armature 78 and relay TS releases allowing the next pulse from relay P to be connected to the upper winding of relay DB. Earth is also extended from armature 40 of relay P, conductor 41, armatures 42, 43, 44 and 45 (Fig. 4), conductor 46, wiper 47 and second bank contact of primary distributor PD¹ to the magnet of the second secondary distributor (not shown). When relay P releases at the end of the pulse the magnet circuit is broken and the wipers of the secondary distributor are moved into contact with the first repeater in the second group.

At the same time relay DB operates fully, opening the circuit of relay P at armature 17 and relay DA at armature 27, thus preventing any more stepping pulses and allowing relay DC to release as its circuit is opened by the restoration of relay DA.

It will be appreciated that at this stage the second group lamp is lit, and the first individual indicating lamp is lit, showing that the first repeater of the second group is being dealt with.

The first secondary distributor SD is returned to its home position owing to a circuit completed by relay TS as follows: earth, armature 88, conductor 89, bank contact 20 and wiper 90 of secondary distributor SD, interrupter springs 91, winding of magnet DM¹ to battery. The magnet drives the wipers to the first contact and since this contact is not earthed, further rotation cannot take place. The routining operations on the repeaters accessible over the secondary distributor will now proceed as before, and when all the twenty have been dealt with, the primary distributor will be advanced a further step, so as to connect up the succeeding secondary distributor. If there are more than 24 secondary distributors as will be assumed in this case,

primary distributor PD² will come into action. When the wipers of the primary distributor PD¹ reach the 25th contact, the test leads are extended to the wipers of primary distributor PD² and thence to the first secondary distributor of this group. Moreover, a circuit is completed for relay DX (Fig. 4) as follows: earth, wiper 92 and 25th bank contact of primary distributor PD¹, conductor 93, armature and front contact 51, winding of relay DX to battery. Relay DX operates and at its armature 81 transfers the stepping circuit to the magnet DM² of primary distributor PD². Consequently, when the next pulse for advancing the primary distributor is received PD¹ remains on the 25th contact, and magnet DM² advances the wipers of primary distributor PD² one step to connect up the 26th secondary distributor i. e. the second one connected to the banks of the second primary distributor.

The subsequent operation of the distributor equipment will be readily understood from the foregoing and when the whole group of repeaters has been dealt with, relay TU (Fig. 6) will operate; this relay being connected to the appropriate contact, for instance, 25, in the bank 94 of the last primary distributor depending upon the number of repeaters to be dealt with. When the last repeater has been tested, earth is extended from wiper 95 and contact 25 of primary distributor PD², conductor 96, armature 53 and front contact, conductor 97, winding of relay TU (Fig. 6 to battery). Relay TU operates and at armature 98 operates alarm relay AM, and at armature 99 lights a lamp to indicate that the routine test is finished. The operation of alarm relay AM disconnects the pulsing circuits from relays P and DR at armatures 18 and 22 respectively, and an audible alarm signal is completed via armature 100, this calling the attention of the testing operator, who observing that the "routine complete" lamp is lit, will restore the start key 10, thereby allowing the various distributor switches to return to normal. A description will now be given of the actual routining operations performed on each repeater.

It will be remembered that relay DB operates when the secondary distributor steps to connect the testing leads to the first repeater to be dealt with. A circuit is thus completed from earth, springs controlled by armature 62 (Fig. 8), conductor 63, armature 64 and front contact, conductor 65 (Figs. 6, 8, 10 and 9), winding of relay RS to battery. The same earth is also extended via resting contacts of key 66 (Fig. 10), conductor 67, wiper 68 of control switch CS, and is maintained on this wiper throughout the test cycle in order to provide operating

70

100

105

110

115

120

125

130

circuits for relays associated with the various testing functions. The operation of relay RS extends earth at its armature 70 over conductor 71, first bank contact and wiper 72 of control switch CS, interrupter springs 73, winding of DM^e to battery, thus causing the control switch to step the wipers to the second contacts. This earth is also extended from wiper 72 via conductor 101 to the winding of relay TB (Fig. 6) and relay TB operates, opening the circuit to the time alarm relay PA (Fig. 5) at armature 102. The function of the time alarm relay PA and also of relay TB will be fully described later.

As previously pointed out, relay TC operated at the time when relay DB was first energized, and relay TC by closing armature 103 extends earth over conductor 104, armature 105 and back contact, conductor 106, upper winding of relay TA (Fig. 7) to battery. Relay TA operates over this circuit and opens armature 107, thus removing the earth which is connected to the second contact of the bank swept over by wiper 72 of the control switch CS in the following circuit: second contact, conductor 117, armature 107 and back contact, conductor 67 (Figs. 7, 8 and 10) resting contact of spring 66, conductor 65 (Figs. 10, 8 and 6) front contact and armature 64, conductor 63, springs controlled by armature 62 to earth. At armature 108 relay TA connects its lower winding over conductor 109, armature 113 and back contact (Fig. 4) conductor 409, wiper 110 of primary distributor PD¹ and its first bank contact, conductor 111, wiper 112 and its first bank contact to the private lead of repeater selected. If the repeater to which the secondary distributor is connected is busy at this time, relay TA will remain held up over its lower winding until earth is removed from the release trunk conductor when the repeater reverts to common use. Thereupon relay TA de-energizes and at armature 108 and back contact again applies earth to the release trunk conductor to busy the repeater to its normal means of access. This guarding earth is derived from armature 31 (Fig. 6), conductor 114, back contact and armature 115 (Fig. 7), back contact and armature 116, back contact and armature 108, conductor 109 (Figs. 7, 8, 6 and 4) armature 113 and back contact, conductor 409 (Figs. 4, 3 and 1) wiper 110 and its first bank contact, conductor 111, wiper 112 and its first bank contact to the private lead of the repeater. Upon the release of relay TA, earth over conductor 67 is connected via armature 107 (Fig. 7), conductor 117, contact 2 and wiper 72 of control switch CS, interrupter springs 73, winding of driving magnet DM^e to battery, thus stepping the control switch to the

third contact as soon as the repeater is available for testing.

It will be noticed that wiper 118 of the control switch is connected to earth at armature 120 of the start relay S over conductor 119, and therefore as the control switch is advanced step-by-step at the satisfactory conclusion of each test, successive indicating lamps are lit, showing at a glance exactly what stage of the test has been reached. The wipers of the control switch are now on the third set of contacts and in this position a circuit is completed for relay TH (Fig. 8) from earth over conductor 67, which, it will be remembered, is earthed during the routine cycle over armature 64 of relay DB, wiper 68 of the sender control switch CS and bank contact 3, conductor 121 (Figs. 3, 5, 7 and 8), winding of relay TH to battery. Relay TH operates and at armature 136 completes the following high resistance loop across the incoming leads to the repeater being dealt with: conductor 122 (Fig. 2), bank contact and wiper 123 of secondary distributor SD, first bank contact and wiper 124 of primary distributor PD¹, conductor 125, back contact and armature 126, conductor 127 (Figs. 4, 6 and 5), armature 128 and back contact, conductor 129 (Figs. 5, 7 and 8), armature 130 and back contact, conductor 131 (Figs. 8, 7, 5, 3 and 4) armature 132 and back contact, conductor 133 (Figs. 4, 3, 5 and 7) right hand winding of relay TF, conductor 134, resistance 146, conductor 134, resistance 135, front contact and armature 136, conductor 137, springs controlled by armature 138, resistance 139, conductor 140 (Figs. 7, 8, 6 and 4) armature 141 and back contact, conductor 142, wiper 143 and first bank contact of PD¹, wiper 144 and bank contact of SD, conductor 145 and from thence to the repeater being dealt with.

The combination of resistances thus connected across the calling loop is of such a value that if the impulse accepting relay of the repeater is in correct adjustment it will not operate. If the relay is too lightly tensioned however, it will operate at this period and reverse the current direction in the calling loop thereby causing the polarized relay TF to operate and close the circuit to relay NOT (Fig. 8) as follows: earth, armature 147, conductor 148, armature 149 and back contact, winding of relay NOT to battery. The operation of relay NOT disconnects the operating circuit of relay ATH at armature 150, thus preventing the stepping of the control switch and stops any further routining.

Assuming that the impulse accepting relay is in correct adjustment, relays TF and NOT will not be operated and routining will continue. Earth at armature 151 of relay DR, which it will be remembered is

pulsing, is extended over conductor 156, armature 152 and back contact, armature 153 and front contact, armature 154 and back contact, upper winding of relay TV to battery. Relay TV operates its light armature 155, over the above circuit, and at the end of the earth pulse, both its windings are connected in series in the following circuit: earth, armature 155, lower winding of relay TV, armature 153 and front contact, armature 154 and back contact, upper winding of relay TV to battery, whereupon the relay operates all its armatures. On the next pulse a circuit is completed as follows: earth, armature 151, conductor 156, armature 152, and front contact, armature 242 and front contact, armature 401 and back contact, armature 150 and back contact, upper winding of relay ATH to battery. Relay ATH operates its light armature 402 and at the end of the pulse operates completely in the following circuit: battery, upper winding of relay ATH, armature 150 and back contact, lower winding of relay ATH, armature 402 and front contact, conductor 67, key 66, conductor 65, front contact and armature 64, conductor 63, springs controlled by armature 62 to earth. Relay ATH opens the circuit of relay TV at armature 154, and at armature 157 completes a circuit for magnet DM^e as follows: earth, armature 156, armature 157, conductor 177, third bank contact and wiper 72, interrupter springs 73, winding of magnet DM^e to battery. Magnet DM^e energizes and opens springs 73 thereby breaking its own circuit, the magnet then de-energizes and the wipers 118, 68, 72 and 326 are stepped onto the fourth set of contacts. Relay TH is released when the wipers of the control switch move off the third set of contacts, and earth is extended from armature 158 over conductor 159 to the fourth contact on which wiper 72 is now resting. Magnet DM^e again operates and then releases to step the wipers onto the fifth set of contacts. Relay ATH remains operated and at armature 160 connects a short-circuit across conductors 434 and 137, which it will be remembered are in series with the calling loop to the repeater; the resultant resistance which is now across the loop is of such a value that the impulse accepting relay should operate. Assuming that the impulse accepting relay in the repeater now operates, the resultant reversal of current in the loop will cause polarized relay TF to operate and complete a circuit as follows: earth, armature 147, conductor 148, armature 149 and front contact, conductor 161 (Figs. 8, 6 and 5), back contact and armature 162, winding of relay OT to battery; relay OT operates and locks to earth in the following circuit: battery, winding of relay OT, armature 162

and back contact, armature 403 and front contact, conductor 404, fourth and fifth bank contacts and wiper 68, conductor 67, to earth at springs controlled by armature 62 (Fig. 8) over a previously traced circuit. Relay OT opens the calling loop to the repeater at armature 128, and also closes a circuit to two-step relay OL as follows: pulsing earth at armature 151 of relay DR, conductor 156, armature 163 and back contact, conductor 164, armature 165, conductor 166, upper winding of relay OL to battery; thus the relay OL operates its light armature 167. At the completion of the pulse, relay OL will operate fully in the following circuit: earth, armature 167, lower winding of relay OL, conductor 164, armature 165 and front contact, conductor 166, upper winding of relay OL to battery. On the commencement of the next pulse from relay DR the driving magnet DM^e of the control switch is energized in the following circuit: earth, armature 151, conductor 156, armature 163 and front contact, conductor 168 (Figs. 8, 7, 5 and 3), winding of DM^e to battery, so that at the completion of the pulse the wipers of the control switch will be moved on to the sixth set of bank contacts. In this position earth is extended from wiper 68 over conductor 169 to relay OTC which operates and locks operated in the following circuit: battery, winding of relay OTC, armature 405, conductor 117 (Figs. 5 and 7), armature 107 and back contact to earth on conductor 67. At armature 406, relay OTC short-circuits resistance 146 from the calling loop to the repeater. Relay OT is released at armature 162 and it again completes the loop to the repeater at armature 128, thereby causing the associated rotary switch to hunt for an idle coder; a reversed battery condition is placed on the calling loop during hunting. Relay TF which is of the shunt field polarized type will be operated from the reversal thus extending earth from armature 147, conductor 148, front contact and armature 170, conductor 171, armature 172 and back contact, conductor 173, armature 174 and back contact, conductor 175, lower winding of two-step relay TM to battery, whereupon relay TM will operate its light armature 176. It will be remembered that during this period the coder finder is hunting, and as soon as a free coder is found the relevant switching relay will be operated thereby restoring normal current flow in the calling loop. Relay TF will release during this condition thereby allowing two-step relay TM to operate completely and lock in the following circuit: battery, lower winding of relay TM, conductor 175, back contact and armature 174, conductor 173, upper winding of relay TM, armature 176 and front contact, ar-

ture 107 and back contact and thence to earth on conductor 67. At armature 178 a circuit is completed for magnet DM⁶ as follows: earth, armature 156 (Fig. 8), armature 157 and front contact, conductor 177, armature 178 and front contact, conductor 179, 6th bank contact and wiper 72, interrupter springs 73, winding of DM⁶ to battery; the wipers are accordingly stepped onto the seventh set of contacts whereupon relay TD operates over the following circuit: earth on wiper 68, seventh bank contact, conductor 180, winding of relay TD to battery. Relay TD in operating completes the following circuit: earth, resistance 181, winding of relay TE (Fig. 7), conductor 182, front contact and armature 183, back contact and armature 184, conductor 185 (Figs. 5, 7, 9 and 10), resting springs of keys 186 and 187, conductor 188 (Figs. 10, 8, 6 and 4), armature 189, conductor 190, wiper 191 and first bank contact of PD¹, wiper 192 and bank contact of SD, to battery over the outgoing negative junction via conductor 193. Relay TE operates and closes the following circuit: battery, winding of relay ATE and front contact, armature 194, conductor 267 (Figs. 7, 8 and 10), resting springs of keys 196 and 197, conductor 198 (Figs. 10, 8, 6 and 4), armature 199, conductor 200, wiper 201 and first bank contact of PD¹, wiper 202 and first bank contact, over conductor 203 to earth over the positive junction outgoing to the distant call indicator office. It will be appreciated therefore that relay TE can only operate if the outgoing negative junction is connected to battery and that relay ATE can only operate if relay TE has operated and if the outgoing positive junction is connected to earth, that is to say, relay ATE can only operate if the outgoing junction lines are continuous and not reversed. Relay ATE in operating, connects earth at armature 204, over conductor 205 to step the control switch CS to its 8th position. A circuit is then completed as follows: earth on wiper 68, eighth bank contact, conductor 206, armature 207 and back contact, winding of relay TN to battery, whereupon relay TN will operate and lock operated in the following circuit: battery, winding of relay TN, armature 208 and front contact, conductor 117 (Figs. 4, 3, 5 and 7), armature 107 and back contact and thence to earth on conductor 67. The operation of relay TN puts the impulsing group of relays into operation, this group comprising relays CC, SC, SW, SZ, (Fig. 9), and E, F, G, and H (Fig. 4). Upon operating relay TN closes the following circuit: earth on wiper 68, eighth bank contact, conductor 206, armature 207 and front contact, conductor 209 (Figs. 4, 6, 8, 10 and 9), interrupter springs 210, armature 211 and back contact, armature 213 and back contact, upper winding of two-step relay CC to battery, thus causing the relay to operate its light armature 212. It will be noticed that when relay TM operated its armature 138 (Fig. 7) a loop was placed across the calling leads to the repeater by way of wipers and bank contacts of secondary and primary distributors, conductor 125, back contact and armature 126, conductor 127 (Figs. 4, 6, and 5), armature 128 and back contact, conductor 129 (Figs. 5, 7 and 8), armature 130, conductor 131, conductor 214 (Fig. 7), armature 215 and back contact, conductor 216, springs controlled by armature 217 (Fig. 5), conductor 218, armature 318, resistance 139, conductor 140, armature 141 and back contact, conductor 142, via wipers and bank contacts of primary and secondary distributors to the repeater. As previously mentioned, the first effective pulse from interrupter springs 210 causes relay CC to operate its light armature 212, at the completion of the pulse the relay operates fully in the following circuit: battery, upper winding of relay CC, back contact and armature 213, lower winding of relay CC, front contact and armature 212, conductor 209, front contact and armature 207, conductor 206, to earth on wiper 68, thereby extending an earth at its armature 219 to operate relay SW.

It must be mentioned here that although pulsing springs 210 and 220, are operating at the same speed conveniently in this case 10 per second, they are arranged to be out of phase with each other i. e. when 210 is closed 220 is open, and it will be readily understood when relay SW breaks its armature 215, the calling loop to the repeater will still be maintained via the now made pulsing spring 220. On the reception of the next pulse from springs 210, earth will be connected over armatures 211 and 221 to the lower winding of relay SC, causing the relay to operate its light armature 222, and it will be appreciated from the foregoing that interrupter springs 220 will now be open, thereby transmitting one impulse to the impulse accepting relay of the repeater under test, which in turn transmits the impulse to the coder in use. At the cessation of the second pulse from springs 210, relay SC will fully operate over both windings in series and will lock up via armatures 223 and 222, and in turn operate relay SZ which short-circuits the pulse springs 220 at armature 407. Relay SZ in operating also breaks the locking circuit of relay CC at armature 213 so that relays CC, SW, SC and SZ will release in turn. When the third pulse is received via interrupter springs 210, relay CC will again commence to operate, and a similar cycle of operations to that already described will ensue. It will be seen therefore that for each complete cycle, the digit one

will be transmitted to the coder and that furthermore, the two-step relays E, F, G and H (Fig. 4) will be operated in turn first partially and then completely by earth extended over conductor 225, at each make and break of armature 224 of relay CC.

When two step relay H operates after the four digit number 1111 has been transmitted into the coder, it extends earth via its armature 226 over conductor 227, so that the control switch CS will be stepped forward onto the ninth set of contacts and a circuit prepared for the reception of the coded pulses. It will be noticed that during the foregoing operations relay TN operated TJ at armature 228, so that earth is connected up over the following circuit: earth, front contact and armature 229, armature 230 and back contact, conductor 231, wiper 232 and bank contact of primary distributor PD¹, conductor 366, wiper 365 and first bank contact of secondary distributor SD; and causes the switching relay HA in the repeater under test to be short-circuited and released, thereby disconnecting the outgoing junction to the call indicator office, so that no equipment shall be operated thereat. Immediately the coder has received its full complement of digits, it will accordingly translate and commence to send out the code over the junction leads, which have been imitated in the routiner. The code for digit one, includes one so-called positive pulse which consists of current flow in such a direction as to operate the positive polarized relay LP which was connected across the outgoing leads by relay TJ. This circuit may be traced as follows: Wiper 192 of secondary distributor SD, first bank contact and wiper 191 of primary distributor PD¹, conductor 190, back contact and armature 189, conductor 188, resting springs of keys 187 and 186, conductor 185 (Fig. 10), armature 184 and back contact, conductor 233 (Figs. 5, 6, and 4), armature 234 and front contact, conductor 235 (Figs. 4, 6 and 8) winding of positive polarized relay LP, conductor 267 (Figs. 8 and 10), resting springs of keys 196 and 197, conductor 198, armature 199 and back contact, conductor 200, wiper 201 and first bank contact of primary distributor PD¹, wiper 202 of secondary distributor SD. Positive polarized relay LP will thus operate four times corresponding to the positive pulse in each of the re-transmitted digits 1111. At each operation LP closes its armature 237 thereby extending the earth from wiper 68 and ninth bank contact of the control switch CS, over conductor 236 (Figs. 3, 5, 7 and 8), front contact and armature 237, conductor 168, winding of magnet DM² to battery, causing the wipers to be moved onto the next set of contacts. It will be noticed that contacts 9, 10, 11 and 12 of the control switch bank associated with wiper

68 are connected together, so as to maintain earth on armature 237 of relay LP while the switch is passing over these positions, and the correct reception of all four of the retransmitted code digits will therefore cause the wipers of the control switch to move to the 13th set of contacts. In this position a circuit is completed as follows: earth on wiper 68, 13th bank contact of control switch CS, conductor 238 (Figs. 3, 5, 7 and 8), winding of slow releasing relay TR to battery. Relay TR operates thereby extending earth at its armature 239, over conductor 240 (Figs. 8, 6, 5 and 3), to the 13th bank contact associated with wiper 72 of the control switch CS, causing the wipers to move to the 14th position. At this period the routiner is so arranged to test the private guard on release feature of the repeater under test, so that when relay TR operates its armature 241, the following sequence of operations will commence. Pulsing earth at armature 151 of relay DR is extended over conductor 156, armature 152 and back contact, armature 241 and front contact, upper winding of relay TV to battery, thus causing the relay to operate its light armature 155, and at the completion of the pulse the relay will operate all its armatures over both windings connected in series in the following circuit: battery, upper winding of relay TV, front contact and armature 241, lower winding of relay TV, front contact and armature 155 to earth. On the commencement of the next pulse, earth will be extended over the now operated armature 152, armature 242 and back contact, winding of relay TW to battery; relay TW operates and completes a circuit for relay TX as follows: earth, armature 239 and front contact, front contact and armature 243, conductor 244, armature 245 and back contact, conductor 246, armature 247 and back contact, conductor 248, upper winding of two-step relay TX to battery.

Relay TX operates its light armature 249 over the circuit described, and at the completion of the pulse after relay TW has released it operates all its armatures over the following circuit: battery, upper winding of relay TX, conductor 248, back contact and armature 247, conductor 246, lower winding of relay TX, front contact and armature 249, conductor 240 (Figs. 7, 5, 6 and 8), front contact and armature 239, to earth. At this stage of the test the private guarding earth from the repeater is extended from wiper 112 of the secondary distributor SD, conductor 111, first bank contact and wiper 110 of primary distributor PD¹, conductor 409, back contact and armature 113, conductor 109 (Figs. 4, 6, 8 and 7), armature 108 and back contact, armature 116, armature 115 and front contact, conductor 250, armature 251 and back

contact, conductor 252, windings of relays TY and ATY in parallel to battery, thus causing both relays to operate. Relay TY closes a locking circuit as follows: battery, 5 winding of relays TY and ATY in parallel, front contact and armature 253, front contact and armature 115, back contact and armature 116, back contact and armature 118, conductor 109, and thence to guarding 10 earth at the repeater. On the next pulse of relay DR relay TW again operates and closes a locking circuit for itself as follows: battery, winding of relay TW, conductor 408, front contact and armature 245, conductor 244, armature 243 and front contact, front contact and armature 239 to earth. Relay TW upon operating closes a point in the circuit of relay GR at armature 258, opens the initial energizing circuit of relays 15 TY and ATY at armature 251 and opens the calling loop to the repeater at armature 130 whereupon the repeater will commence to release. When the guard relay of the repeater under test has released consequent on 20 the disconnection of the impulse accepting relay, a high resistance relay is connected in series with the private lead, and although the high resistance relay is energized in this circuit the reduction of current in the circuit causes relays TY and ATY to release. 25 Immediately armature 253 of relay TY leaves its front contact the circuit of said high resistance relay in the repeater will be broken and it will thereupon release and again extend a full earth over the private lead. At this period however, relay TW is being held operated and hence relay ATY will remain de-energized. Earth is now extended from the private lead over conductor 30 109, armature 108 and back contact, armature 116 and back contact, armature 115 and front contact, armature 253 and back contact, armature 407 and back contact, winding of relay TZ to battery. Relay TZ operates over this circuit and closes the following circuit: earth, armature 254 and front contact, conductor 260 (Figs. 7, 5 and 3), 35 14th bank contact and wiper 72, interrupter springs 73, winding of magnet DM⁶ to battery. The wipers of the control switch are thereby stepped onto the 15th set of contacts.

It will be appreciated from the foregoing, that the test imposed on the repeater at this period consists of the reception of a guarding earth, a complete opening of the calling loop, a high resistance earth period, and then a re-guarding earth when all preceding switches have released. If, however, the repeater fails to comply with any one of the above conditions, relay GR will be operated over the following circuit: earth, armature 254 and back contact of relay TZ, armature 255 and back contact, front contact and armature 256, conductor 257, front contact and armature 258, conductor 259, winding of relay GR to battery; relay GR operates in this circuit and extends earth over armature 116 and conductor 109 to guard the repeater and enable the fault 50 to be located.

In the course of a successful test the circuit of relay GR is completed when relay ATY releases after relay TW has locked operated, i. e. when the inclusion of the high resistance relay in the circuit of relay ATY has caused relay ATY to release and close armature 255, whereas the circuit of relay TZ is not completed until the high resistance relay has released due to its circuit 75 being opened by the release of relay TY, and hence it is essential that relay GR shall be slow to operate, to enable the fast operating relay TZ to energize first and open the circuit of relay GR at armature 254 and 80 allow the routine cycle to continue.

Two further pulses are then sent to magnet DM⁶ over the following circuit: earth, armature 254 and front contact, conductor 260 (Figs. 7, 8 and 6), armature 261 of 85 pulsing relay DR, conductor 168, winding of driving magnet DM⁶ to battery, thereby causing the wipers of the control switch to be moved into the 17th position. When the wipers of the control switch move into 90 the 17th position the circuit of slow-releasing relay TR over conductor 238 is opened, and the earth on wiper 68 is now extended over the 17th contact, conductor 262, winding of relay TG to battery. Relay TG 95 operates over the circuit described and locks up in the following circuit: battery, winding of relay TG, armature 263 and front contact, conductor 117 (Figs. 5 and 7), armature 107 and back contact and thence to 100 earth over conductor 67. Relay TG extends battery and earth via the windings of relay R (Fig. 9) to operate the switching relay in the repeater under test. The earth may be traced as follows: earth, resistance 276, 105 key 275, key 274, lower winding of relay R, conductor 273 (Figs. 9, 7 and 4), back contact and armature 272, armature 271 and back contact, armature 268 and front contact, conductor 267 (Figs. 5, 7, 8 and 10), 110 key 196, key 197, conductor 198, armature 199 and back contact, conductor 200, primary and secondary distributors to the positive outgoing junction. The battery may be traced as follows: battery, resistance 277, 115 key 278, key 279, upper winding of relay R, conductor 280 (Figs. 9, 7 and 8), back contact and armature 281, conductor 282 (Figs. 8, 7 and 5), armature 283 and back contact, front contact and armature 184, conductor 120 185 (Figs. 5, 7, 9 and 10), key 186, key 187, conductor 188 (Figs. 10, 8, 6 and 4), armature 189 and back contact, conductor 190, primary and secondary distributors to the negative outgoing junction. During the 125 130

operation of relay TG, relay TR was holding due to the retaining effect of the copper slug on its core, however, when the magnetic flux finally subsides, relay TR will release. 5 It will be remembered that the holding circuit for relay TX extended from armature 239 over conductor 240 and that the holding circuit for relay TW extended from armature 239 over conductor 244, hence when 10 armature 239 opens the relays TX and TW will release, the locking circuit of relay TV is opened at armature 241 and relay TZ will finally release due to its disconnection at armature 115 of relay TX.

15 A circuit may now be traced for stepping the control switch as follows: earth, armature 264 of relay TW, conductor 265 (Figs. 8, 7, 5 and 3), 17th bank contact and wiper 72, interrupter springs 73, winding of magnet DM⁶ to battery, so that the wipers will now be moved into the 18th position, where earth is extended via wiper 68, conductor 266, winding of relay TK to battery.

20 Relay TK operates and locks up in the following circuit: battery, winding of relay TK, armature 269 and front contact, armature 270 and back contact, conductor 117, armature 107 and back contact and thence to earth on conductor 67. At armatures 271 and 283 relay TK reverses battery over the junction to imitate the distant call indicator operator answering. The circuit may be traced from, the negative outgoing junction 193, secondary and primary distributors, conductor 190, back contact and armature 189, conductor 188, resting springs of keys 187 and 186 (Fig. 10), conductor 185, armatures 184, 271 and 272, conductor 273, lower winding of relay R (Fig. 9) resting 25 springs of 274 and 275 through resistance 276 to earth; and following the other part of the circuit; battery via resistance 277 (Fig. 9), resting springs of keys 278 and 279, upper winding of relay R, conductor 280, armature 281 (Fig. 8), conductor 282, armatures 283 and 268 (Fig. 5), conductor 267, resting springs of keys 196 and 197, conductor 198, armature 199, conductor 200, wiper 201 and first bank contact of primary 30 distributor PD¹, to wiper 202 of secondary distributor SD and positive outgoing junction 203. The above current reversal causes the polarized relay in the repeater to operate, and consequently, battery and earth 35 connections from the impulse accepting relay are reversed to the shunt field polarized relay TF in the routiner by way of earth via winding of impulse accepting relay in the repeater, (conductor 122) first bank contact and wiper 123 of secondary distributor SD, first bank contact and wiper 124 of PD¹, conductor 125, armature 126, conductor 127, armature 128 (Fig. 5), conductor 129, armatures 130 and 284 in parallel, conductor 131, winding of relay TL, right-

hand winding of relay TF, conductor 134, armature 217, conductor 218, armature 138, resistance 139 (which is approximately equivalent to the maximum junction resistance), conductor 140, armature 141 (Fig. 4), conductor 142, wiper 143 and first bank contact of primary distributor PD¹, wiper 144 and first bank contact of secondary distributor SD, to battery via the other winding of the impulse accepting relay in the repeater. Relay TF operates over the circuit described and completes a circuit for magnet DM⁶ as follows: earth, armature 147, conductor 148, front contact and armature 170, conductor 171, armature 172 and front contact, conductor 285, 18th bank contact and wiper 72 of the control switch CS, interrupter springs 73, winding of magnet DM⁶ to battery, thereby causing the switch CS to move its wipers on to position 19, thus proving that the battery reversal from the repeater has been received. In the 19th position of the control switch CS, earth on wiper 68 is connected over conductor 286, winding of relay HG, resistance 410 to battery. Relay HG operates and locks up in the following circuit: battery, resistance 410, winding of relay HG, armature 287, conductor 117, armature 107 and back contact to earth on conductor 67. One of the functions of relay HG is to extend interrupted ringing current from conductor 288 via condenser 411, armature 289 and front contact, armature 290 and front contact, conductor 291, armature 292 and back contact, conductor 273 (Figs. 7 and 5), armatures 272, 271 and 184, conductor 185 (Figs. 5, 7, 9 and 10), keys 186 and 187, conductor 188, armature 189 and back contact, conductor 190, primary and secondary distributors to negative outgoing junction 193. If the circuit through the talking condenser of the repeater is closed, ringing current will flow back to the routiner via conductor 122, bank contact and wiper 123, bank contact and wiper 124 of primary distributor PD¹, conductor 125, armature 128, back contact and armature 126, conductor 127 and back contact, conductor 129, armature 284 and back contact, back contact and armature 293, conductor 294, front contact and armature 295, front contact and armature 296, condenser 412, winding of relay HF to earth. Relay HF is energized over this circuit and at its armature 297 extends earth over conductor 298, winding of relay AR to battery, so that relay AR operates and shunts its winding by a resistance 413, thereby rendering its slow-to-release to enable it to hold up during the pulsating earth from relay HF. When relay HG operated, the pulsing earth at armature 151 of relay DR (Fig. 6) was extended over conductor 301, armature 300 and back contact, armature 299 and front contact, lower 130

winding of two-step relay PD to battery, causing the relay PD to operate its light armature 302, so that when the pulse goes off the relay operates all its armatures via both windings in series over the following circuit: battery, lower winding of relay PD, front contact and armature 299, upper winding of relay PD, front contact and armature 302 to earth. At armature 300 relay PD closes the following circuit: pulsing earth at armature 151 of relay DR, conductor 301, armature 300 and front contact, conductor 303, 19th bank contact and wiper 72, interrupter springs 73, winding of magnet DM⁶ to battery, so that the control switch moves its wipers into the 20th position; moreover, when relay AR (Fig. 7) again operates on the next ringing period a circuit will be completed as follows: earth at wiper 68 of the control switch and 20th bank contact, conductor 304, armature 395 and front contact, winding of relay LD to battery, causing the relay to operate and complete the circuit to the lower winding of relay KO. Relay KO will operate its light armature 306 over this circuit, and when the ringing period ceases relay LD will release and allow KO to operate fully. It will be appreciated that when armatures 292 and 293 of relay KO are operated, the subsequent ringing period will be delivered over the other side of the transmission circuit, and if this proves to be sound, relays HF, AR and LD will again operate thereby short-circuiting relay HG over a circuit, earth at armature 307 of LD, (Fig. 7) armature 308, conductor 309 to the battery side of the winding of relay HG. Relay HG releases after its slow period and extends earth at its armature 310 over conductor 311, to step the control switch wipers on to the 21st contact, where earth at wiper 68 is connected over conductor 312, armature 313 and front contact, winding of relay TQ to battery. Relay TQ operates over the circuit, and locks at its armature 314, conductor 315, and armature 316 of relay TL to earth, thereby disconnecting the locking circuit of relay TK at armature 270. Relay TK in releasing allows earth on wiper 68 to be connected over conductor 312, armature 313 and back contact, conductor 317, pulsing armature 318, conductor 319, winding of relay TP to battery, and relay TP operates and locks up at its armature 320. The operation of relay TP imitates a busy flash condition from the distant call indicator office, by disconnecting earth from the lower winding of relay R at armature 272, and substituting alternate earth and battery over conductor 321 via pulsing armature 322 of relay DR. On the first battery period at armature 322, battery is connected over both junction lines via the said armature 322 and the upper

winding of relay R, thereby causing the release of the high impedance relay in the repeater which is bridged across the lines.

A busy flash condition is thereby set up in the repeater which consists of battery and earth via the impulse accepting relay being alternately substituted by battery over both windings, and it will be apparent after tracing the circuit previously described over wipers 144 and 123, of the secondary distributor SD, that relay TL, which is connected across the incoming lines (Fig. 7) will therefore release when the said battery is applied to both lines. When relay TL releases on the first battery period it opens its springs 316, thus disconnecting the locking circuit of relay TQ which releases; on the next operation of relay TL, a circuit is completed as follows: earth at armature 316, conductor 315, armatures 314 and 323, conductor 324, 21st and 22nd bank contacts and wiper 72 of the control switch, interrupter springs 73, winding of magnet DM⁶ to battery, thereby causing the control switch to move its wipers into the 23rd position. Earth at wiper 68 of the control switch is now extended over conductor 69 to relay TO (Fig. 6), which operates, and disconnects the circuit of relay DB at armature 39, thus completing a stepping circuit from earth at armature 62 on relay KA (Fig. 8), conductor 63, armature 64, conductor 325, 23rd bank contact and wiper 326, interrupter springs 73, winding of magnet DM⁶ to battery, causing the control switch to be stepped to the 24th position.

Relays DA, DB and TC will now commence to operate, thereby stepping the secondary distributor on to the next repeater to be dealt with, and the sequence of operations from this point will be as previously described.

It will have been noticed that the operating and holding earth for most of the relays is supplied via the resting contacts of relay TA and it will also be remembered that relay TA operates at the beginning of the routine cycle, to test the condition of the release trunk of the repeater. As soon therefore as relay TA operates, this operating and holding circuit is broken, and those relays which have been locked energized will restore. Indicating lamps showing the progress of the test are connected in circuit over wiper 118 of the control switch and as each test is performed the appropriate lamp is lit. The various indicating lamps are lighted in the following positions of the control switch:

1. Hunting unequipped positions. 125
2. Repeater busy.
3. Non-operate test impulse accepting relay.
5. Operate test impulse accepting relay.
6. Reverse battery, finding coder. 130

- 7. Junction loop.
- 8. Pulsing into coder.
- 9. Code sending.
- 10. First digit received.
- 5 11. Second digit received.
- 12. Third digit received.
- 13. Fourth digit received.
- 14. Private guard on release.
- 15. Private guard calling loop opened.
- 10 16. Private guard calling loop opened.
- 18. Supervisory battery reverse metering.
- 20. Transmission test.
- 21. Busy flash test.
- 22. Busy flash test.
- 15 23. Test cycle completed.
- 24. Test cycle completed.
- 25. Test cycle completed.

Hence the attendant is able to note at any time which test is being conducted and 20 since the control switch is maintained in position in the event of a fault being found and the test stopped, the nature of the fault is at once indicated.

It will be seen that with relays S and DB 25 operated, as the commencement of the test cycle, earth pulses at armature 327 of relay DR (Fig. 6) will be extended over conductor 328, armature 329 and back contact, conductor 330, armature 331, armature 102, 30 conductor 332, upper winding of relay PA to battery. Relay PA operates its light armature 333 over the circuit described and locks up on both windings in series thereby extending the pulsing circuit to relay APA 35 which also operates in two steps and finally extends the pulsing circuit on to the time alarm relay TAR. The latter relay which is of known construction consists of a stepping magnet and a pawl acting on a toothed 40 wheel, together with a locking ratchet controlled by another magnet.

The pulses are conducted over the circuit 45 previously mentioned and via armature 329 and 334, stepping winding of relay TAR to battery, and at the same time a circuit 50 for the holding winding of the time alarm relay is completed from earth at armature 335. After a pre-determined time, conveniently 3 minutes, relay TAR will have 55 stepped sufficiently far to close its contacts 336, thereby operating alarm relay AM over conductor 337. Relay AM opens the circuit of relay DR at armature 22 whereupon relay DR releases and disconnects the stepping circuit of the time alarm relay TAR 60 at armature 327. At armatures 100 and 338 relay AM connects earth to an alarm and indicating circuit and also to an extended alarm circuit, through springs of key 339.

65 It therefore follows that if the time alarm relay is permitted to operate uninterruptedly for the period for which it is set, the alarm will be given. While the test is progressing, satisfactorily however, relay TB (Fig. 6), which is connected in parallel with

the control switch magnet, always operates each time the magnet of the control switch is energized, thereby breaking the circuit of the time alarm train of relays at armature 102, allowing them to restore. When a fault 70 is encountered the control switch will not step, hence relay TB will not be operated and after a suitable period an alarm will be given. The position of the control switch will indicate the nature of the fault, and the 75 group and individual lamps will indicate on which repeater the fault occurred. The reset key 66 (Fig. 10) is employed to restart the test cycle after it has been stopped due to a fault, and at its left hand contacts extends earth from armature 62 of relay KA (Fig. 8), conductor 63, armature 64, conductor 65, front contacts of key 66, conductor 325, bank contacts and wiper 326 of control switch CS, interrupter springs 73, 80 winding of magnet DM⁶ to battery; earth over conductor 340 via the commoned bank of the control switch is extended via key 66 and conductor 341, upper winding of relay RR (Fig. 8) to battery, thus causing the 85 relay RR to operate and close a circuit for relay TC at armature 342 and conductor 343. Relay TC in operating completes a locking circuit for relay RR from earth at armature 103, conductor 104, armature 105 90 and front contact, lower winding of relay RR to battery; and also extends earth at armature 334 and conductor 335, 24th bank contact associated with wiper 72 of the control switch, interrupter springs 73, winding 95 of magnet DM⁶ to battery, thereby causing the control switch to step into its 25th position. A homing circuit is now completed for the magnet DM⁶ as follows: earth, 25th bank contact and wiper 326, interrupter 100 springs 73, winding of magnet DM⁶ to battery, thereby causing the switch to rotate to the first bank contact and when the key 66 is released, the test cycle will again commence.

110 It will be appreciated that alarm circuits may be provided for the driving magnets of the various rotary switches in order to give an alarm should any of the switches stick during rotation. Such a circuit could take the form of a low resistance relay in series with the battery feed to the rotary switches, so that in the event of a magnet being energized for an undue period of time, the said relay could be arranged to connect 115 up an alarm.

120 The step-on key 349 (Fig. 6) is used if it is desired to pass from one repeater circuit to another, as for example if a fault be found on a repeater, so that the entire 125 routining operation may not be held up while this fault is being dealt with. The operation of the step-on key will step the secondary distributor to the next repeater and bring the control switch back to the 130

first position so that the routine test may be carried out on the next repeater. When the step-on key 349 is operated, earth is extended over conductor 350, armature 351, conductor 352, armature 353, conductor 354, winding of relay KA and resistance 414 to battery, whereupon KA operates and at armature 62 completes a circuit to relay K from earth at armature 62, conductor 335, armatures 356 and 357, winding of relay K to battery. Relay K operates, thereupon at armature 358 extending earth over conductor 325 and wiper 326 to start the control switch homing. If it is desired to step 10 from a repeater which is the last accessible from a particular secondary distributor, it being then necessary to operate primary distributor PD, a circuit is prepared at armature 359 for relay TO over conductor 74 from earth at wiper 60 of the secondary distributor SD in parallel with the 20th indicating lamp. The operation of relay TO and its action in stepping the primary distributor has been previously described.

25 The operation of relay KA releases relay DB at armature 36, thereby allowing the secondary distributor to be stepped once, and the routine cycle will be commenced on the next repeater, and will proceed as previously described. When the key 349 is released, relay KA releases but relay K remains operated over the following circuit: battery, winding of relay K, armature 357 and front contact, armature 356 and back 30 contact, front contact and armature 358, back contact and armature 64, conductor 63, springs controlled by armature 62 to earth. When relay DB is again operated after the secondary distributor has stepped, the holding circuit of relay K is opened at armature 64 and relay K releases thus restoring conditions for testing the next repeater.

If it is desired to perform a continuous routine on one particular repeater, the start 45 key 10 is restored allowing the various distributing switches which may be off normal to return to the home position. The continuous routine key 344 (Fig. 10) is then thrown and causes operation of relay CR over conductor 345. At armature 360 relay CR closes a circuit for relay SS which operates and prepares the stepping circuits which will be described later. Relay CR opens the stepping circuit of the primary 50 and secondary distributors at armatures 80 and 44. If the primary stepping key 348 (Fig. 4) is now operated, a circuit is completed from earth, springs of start key 10 (Fig. 10), conductor 347, springs of primary stepping key 348, armatures 80 and 81, conductor 82, winding of driving magnet DM¹ to battery. Intermittent operation of the key 348 therefore, will stop the first six wipers of the primary distributor PD¹ to 55 the required secondary distributor and due

to earth on wiper 58 the magnet DM⁵ controlling the second six wipers of the primary distributor will also be operated, so that the 12 wipers will be moved into contact with the required secondary distributor as indicated by the lighting of the appropriate group indicating lamp. To step the secondary distributor to the required repeater, the secondary stepping key 346 is extended from the start key 10, conductor 70 347, stepping key 346, armatures 44 and 45, conductor 46, wiper 47 and bank contact of primary distributor PD¹, winding of driving magnet DM¹ to battery, thereby bringing the secondary distributor wipers 75 into engagement with the required repeater as shown by the lighting of the proper indicating lamp. The operation of the start key 10 will then start the routining cycle and so long as the continuous routine key 80 is kept in the operated position, the test cycle will continue on the same repeater, since as previously pointed out the operation of relay CR opens the stepping circuit to the distributors. 85

If the required repeater had been connected to a secondary distributor to which access was obtained from the second primary distributor, the operation of the distributor selecting key 361 avoids the necessity for stepping the first primary distributor around its banks to reach the second primary distributor. When key 361 (Fig. 10) is operated, earth is extended over operated springs of keys 344 and 361, conductor 362, 90 to relay SA which operates and transfers the testing leads to the wipers of the second primary distributor. The operation of the distributor selecting key 361 also extends earth over conductor 93, and armature 51 95 (Fig. 4) to operate relay DX, so that the operation of the primary stepping key 348 will now cause the wipers of the second primary distributor PD² to be moved to the required secondary distributor, and then the 100 operation of the secondary stepping key 346 will bring the wipers of the secondary distributor into engagement with the required repeater, and the routine test can then be started by operating the start key 10. Test 105 keys 274, 275, 278 and 279 (Fig. 9) are provided to enable more severe operating conditions to be imposed upon the junction relays in the repeater, to ensure that the relays are in correct adjustment. In order 110 that the correct functioning of the routining equipment may be checked from time to time, fault imitation keys are included in the circuit. These comprise the following 115 keys, disconnect negative junction key 186 (Fig. 10) disconnect positive junction key 196, outgoing lines reversed keys 187 and 197 and repeater busy keys 363 and 364 (Fig. 3). The effect of the operation of 120 these keys will be readily apparent from 125 130

the drawings, and will result in the stopping of the test cycle as soon as the particular test concerned is reached, thereby bringing in the time alarm. It will be appreciated that other functions of the routining equipment could readily be checked by the provision of suitable additional fault imitation keys. If under any conditions repeaters are not fitted in their appropriate positions, for example, in the case of spare positions the secondary distributor is made to pass over such positions by earthing the relevant contacts associated with wiper 365 of the secondary distributor. When the secondary distributor reaches such a position, the earth is extended over conductor 366', bank contact and wiper 232, conductor 231, armatures 230 and 229 (Fig. 4), conductor 365, armature 366, conductor 350, armature 351, conductor 352, armature 353, conductor 354, winding of relay KA, resistance 414 to battery, whereupon relay KA will energize; the ensuing circuit operations will then be similar to those described for the operation of the step-on key, and the secondary distributor will pass on to the next repeater. If a secondary distributor is not available, the primary distributor may be stepped past that position by earthing the relevant bank contact associated with wiper 367 (Fig. 1), and as soon as the wipers reach such a contact, relay TS will operate from earth on wiper 367, conductor 76, armature 77 (Fig. 4), winding of relay TS to battery. The operation of relay TS will allow a further pulse to be extended to the primary distributor magnet, thereby causing it to move the associated wipers past the unequipped position.

40 What I claim as new and desire to secure by Letters Patent is:—

1. In an automatic telephone system employing a plurality of similar pieces of apparatus having incoming and outgoing conductors including condensers in the conductors, a routine test mechanism for automatically testing said apparatus, means for associating said test mechanism directly with the incoming and outgoing conductors of one of said apparatus, and means in said test mechanism for testing the condition of the condensers in said conductors.

2. In an automatic telephone system employing a plurality of similar pieces of apparatus, routine testing mechanism associated therewith, means in said testing mechanism for connecting with one of said pieces of apparatus to perform a number of tests on it, one of said tests comprising means for releasing said apparatus and temporarily extending guarding potential to it, a slow-to-energize relay in said testing mechanism initially energized when said guarding potential is applied and completely energized 60 when said apparatus releases due to the re-

moval of said potential, and means in said testing mechanism responsive to the operation of said slow-to-energize relay for stopping the testing of said apparatus and operating on alarm signal if the release time 70 of said apparatus is too short.

3. In an automatic telephone system employing a plurality of similar pieces of apparatus each having a high resistance relay, a guard relay and a test conductor, a routine testing mechanism operable to connect with each piece of apparatus and perform a series of tests thereon, means in said test mechanism for operating said high resistance relay and guard relay in said apparatus to connect guarding potential to the test conductor of said apparatus, means for releasing said guard relay and connecting said high resistance relay in series with said test conductor, a relay in said test mechanism controlling a point in the circuit of said high resistance relay and operated by said guarding potential, and means responsive to the connection of said high resistance relay to said test conductor for releasing said relay in said testing mechanism to open the circuit of said high resistance relay. 80 90

4. In an automatic telephone system employing a plurality of similar pieces of apparatus each having incoming and outgoing 95 talking conductors including condensers in the conductors a routine testing mechanism for performing a series of tests on each piece of apparatus, means for associating said testing mechanism directly with the incoming and outgoing talking conductors of the apparatus, an alternating current relay in said testing mechanism, and means in said testing mechanism for transmitting ringing current to each of said talking conductors in turn and through the condensers to effect the operation of said alternating current relay. 100 105

5. In an automatic telephone system employing a plurality of similar pieces of apparatus, each having a high resistance relay, a guard relay, and a test conductor, a routine testing mechanism operable to connect with each piece of apparatus and automatically perform a series of tests thereon, means in said test mechanism for operating said high resistance relay and guard relay in said apparatus to connect guarding potential to the test conductor of said apparatus, means responsive to the release of said guard relay for connecting said high resistance relay in series with said test conductor, a relay in said test mechanism controlling a point in the circuit of said high resistance relay and operated by said guarding potential to lock itself energized to said test conductor, means responsive to the connection of said high resistance relay to said test conductor for releasing said relay in said test mechanism to open the circuit of said high resistance relay and to again apply guarding po- 110 115 120 125 130

tential to said test conductor, and another relay in said testing mechanism connected to said test conductor and operated by said guarding potential for continuing the testing of said piece of apparatus.

5 6. In an automatic telephone system employing a plurality of similar pieces of apparatus each having a high resistance relay, a guard relay, and a test conductor, a routine testing mechanism operable to connect with each piece of apparatus and perform a series of tests thereon, means in said test mechanism for operating said high resistance relay and guard relay in said apparatus to connect guarding potential to the test conductor of said apparatus, means for releasing said guard relay and connecting said high resistance relay in series with said test conductor, a slow-to-energize relay in said 10 testing mechanism controlling said high resistance relay and operated by said guarding potential to stop the test of said apparatus and operate an alarm signal, and means responsive to the release of said apparatus 15 for opening the energizing circuit of said slow-to-operate relay.

20 7. In an automatic telephone system employing a plurality of similar pieces of apparatus having incoming and outgoing conductors in each piece of apparatus, a routine testing mechanism for automatically performing a series of tests on said apparatus, means for associating said testing mechanism directly with the incoming and 25 outgoing conductors of a piece of apparatus, means in said test mechanism for reversing the connections of said outgoing conductors to effect a consequent current reversal in said incoming conductors, and a polarized 30 relay in said testing mechanism connected to said incoming conductors and operated by 35 said current reversal to effect the continuation of the tests on said apparatus.

40 8. In an automatic telephone system employing a plurality of similar pieces of apparatus having incoming and outgoing conductors for each of said pieces of apparatus, a routine testing mechanism for automatically performing a series of tests on 45 said apparatus, means for associating said testing mechanism directly with the incoming and outgoing conductors of a piece of apparatus, means in said testing mechanism for applying busy flash conditions to said 50 outgoing conductors to effect consequent intermittent equalization of potential in said incoming conductors, and a relay in said testing mechanism connected to said incoming conductors and released by said 55 intermittent potential to effect the continuation of the tests on said apparatus.

60 9. In testimony whereof I have signed my name at London, England, this 4th day of September, 1928.

65 OWEN AVIS PEARCE.
